CLAIM

The ornamental designs for a “coke oven corbel gas offtake module component”, as shown and described.

DESCRIPTION

FIG. 1 depicts a to left rear perspective view of a coke oven corbel gas offtake module component which embodies my new and original design therefore, wherein

FIG. 2 is a right rear perspective view of thereof;

FIG. 3 is a right front perspective view thereof;

FIG. 4 is a left front perspective view thereof;

FIG. 5 is a rear end elevational view thereof;

FIG. 6 is a front end elevation view thereof;

FIG. 7 is a top plan view thereof;

FIG. 8 is a bottom plan view thereof;

FIG. 9 is a left side elevation view thereof; and,

FIG. 10 is a right side elevation view thereof.

The broken lines appearing in FIGS. 1-4 and 7-8 illustrate portions of the “coke oven corbel gas offtake module component” that form no part of the claimed design.
